UNITED STATES PATENT OFFICE

2,033,434

BOILER CLEANER

Frederick W. Linaker, St. Louis, Mo.

Application November 28, 1934, Serial No. 755,136

5 Claims. (Cl. 122—392)

My invention has relation to improvements in boiler cleaners and it consists in the novel features of construction more fully set forth in the specification and pointed out in the claims.

5 The present invention is concerned more particularly with the means for supporting the operating head of the boiler cleaner rather than the construction of the head itself. The principal object of the invention is to support the 10 boiler cleaner from the tubes of the boiler instead of from the boiler wall so that the boiler cleaner will be carried with the tubes during the expansion and contraction thereof and so the contraction and expansion of the boiler wall 15 will in nowise effect the boiler cleaner which passes freely through said wall.

A further object of the invention is to provide 20 a support for boiler cleaners for carrying the weight of the operating head irrespective of the construction thereof so that the supporting means may be applied to any type of boiler cleaner.

Other objects of the invention and advantages 25 inherent therein will be better apparent from a detailed description of the same in connection with the accompanying drawing, in which:

Figure 1 is a vertical cross-section through a 30 portion of the boiler wall and the first two boiler tubes adjacent thereto showing my improved boiler cleaner support and the boiler cleaner carried thereby, said boiler cleaner being shown in elevation; Fig. 2 is a vertical, transverse section taken on the line 2—2 of Fig. 1; and Fig. 3 is a vertical, cross-section taken on the line 3—3 of Fig. 1 with the boiler cleaner support and boiler tubes carrying the same 35 shown in elevation.

Referring to the drawing, W represents the 40 boiler wall and T represents adjacent tubes of the boiler on which is secured my improved boiler support S for the boiler cleaner operating head H. The operating head H forms no part of the present invention except that the supporting bracket 1 for the operating head is provided with a ring 2 having an external channel 45 3 for receiving a saddle 4, which is a part of the boiler cleaner support, as will be more fully described hereinafter.

In the present invention the support S is 50 anchored to the boiler tubes T, said support comprising a tubular member 5, the outer enlarged end 6 of which is provided with internal threads 7 and a rib 8 extending downwardly and inwardly from the bottom of the tubular portion 5, which rib terminates in a heel 9 of

arcuate formation for abutment against one of the tubes T. Disposed below and transversely of the tubular portion 5 is a semi-cylindrical socket 10 for receiving one of the boiler tubes T on which the support is clamped by means of the clamp members 11, 11 which embrace the tube T and are secured in spaced relation to the lateral flanges 12, 12 and 13, 13 extending laterally from the socket 10. The clamp members 11, 11 are also provided with flanges 14, 14 through which bolts 15, 15 pass for fastening the clamp members to the socket member whereby the tube T is firmly clamped. The supporting member S projects into an opening O provided in the boiler wall W in which opening is fitted a wall sleeve 16 of rectangular cross-section. The wall sleeve 16 is provided with a flange 17 fitting against the outer surface of the boiler wall and suitable bolts 18 pass through said flange to secure the wall sleeve in place. 20

Formed within the wall sleeve 16 is an annular flange 19 through which passes a tube 20, the inner end of which is screw-threaded into the enlarged end 6 of the tubular member 5. The outer end of the tube 20 carries a bracket 21 which has a bearing portion 22 traversed by the tube 20 and an outwardly projecting shelf 23 which carries the saddle 4. A set-screw 24 passes through the bearing portion 22 to firmly secure the bracket 21 and tube 20 together. A pair of oppositely disposed lugs 25, 25 project downwardly from the saddle 4 so as to provide a channel 26 between them, which channel receives the shelf 23 to which the saddle is secured by means of set-screws 27, 27. The bracket 21 has lateral enlargements 28, 28 provided with threaded openings 29, 29 to receive set-screws 30, 30 for adjusting the position of the bracket, and lock-nuts 31, 31 are provided to hold the studs in their adjusted position. 40

An abutment plate 32 is mounted on tube 20 in abutting relation with the bearing 22 and a sealing plate 33 is also mounted on the tube 20 in abutting relation with the inwardly turned end 19' of flange 19, the sealing plate 33 being held in intimate relation with the flange 19 by a coiled spring 34. The purpose of the sealing plate 33 is to maintain the opening in the flange 19 tightly closed, irrespective of movements of the tube 20 relative to the boiler 50 wall W, it being understood that the tube 20 being a part of the boiler cleaner, is carried by and moves with the boiler tubes.

The bracket 21 serves to directly support the head H of the boiler cleaner and is maintained 55

in fixed position by its abutting relation against flange 17 of the wall sleeve 16, and the tubular member 5 serves to anchor the bracket 21 on the boiler tubes T. Thus the entire boiler cleaner support S bears against the boiler wall and is anchored to the boiler tubes T.

Having described by invention, I claim:

1. In combination with a boiler cleaner adapted to traverse an opening in the boiler wall, a support for the boiler cleaner comprising an anchor member mounted on the boiler tubes, an abutment member connected thereto and abutting against the outer surface of the boiler wall, and an adjustable saddle mounted 15 on the abutment member, said boiler cleaner resting on the saddle.

2. In combination with a boiler cleaner for removing deposits from the tubes of boilers, a support for the boiler cleaner bearing against 20 the boiler wall and anchored to the boiler tubes, said support including a tubular member clamped against one of the boiler tubes and braced against another of said tubes.

3. In combination with a boiler cleaner for

removing deposits from the tubes of boilers, a support for the boiler cleaner anchored to the boiler tubes, said support including a bracket abutting against the boiler wall, and means for adjusting the spacing of said bracket from the 5 wall.

4. In combination with a boiler cleaner comprising a blower tube and an operating head therefor, a support for the boiler cleaner comprising a tubular member traversed by the 10 boiler cleaner, said tubular member including means for securing the same to the boiler tubes, and an abutment member carrying the boiler cleaner head, said abutment member being fixed to the tubular member and having abutment 15 against the outer surface of the boiler wall.

5. In combination with a boiler cleaner for removing deposits from the tubes of boilers, a support for the boiler cleaner, said support including a member clamped against one of the 20 boiler tubes and braced against another of said tubes.

FREDERICK W. LINAKER.
